UNITED STATES PATENT OFFICE

GEORGE K. BAINBRIDGE, OF RIPON, CALIFORNIA

PLASTIC ROLLING MACHINE

Application filed May 24, 1930. Serial No. 455,236.

This invention relates to machines for rolling individual lumps of plastic material from rectangular, cylindrical or other shapes into balls of even and substantially spherical form; and particularly represents improvements over the structure for the same purpose shown in my Patent No. 1,303,013, dated May 6, 1919.

The major object of the present invention is to provide a machine for this purpose in which the rolling of the lumps into a spherical form is more quickly and accurately accomplished than with the present machine; there is no chance for the lumps to become wedged between the rolling surfaces; and the driving of the double-motion belt in the necessary directions is simplified by reason of the improved mounting and operation of the belt support.

20 A further object of the invention is to produce a simple and inexpensive device and yet one which will be exceedingly effective for the purpose for which it is designed.

These objects I accomplish by means of such structure and relative arrangement of parts as will fully appear from a perusal of the following specification and claims.

In the drawings similar characters of reference indicate corresponding parts in the several views:

Fig. 1 is a side elevation of my improved rolling machine.

Fig. 2 is a partial top plan view of the same.

Fig. 3 is an enlarged fragmentary cross section on the line 3—3 of Fig. 1.

Referring now more particularly to the characters of reference on the drawings, the machine comprises transversely spaced uprights 1 which support horizontal frame members 2 on which longitudinally spaced rollers 3 are mounted. An endless belt passes about these rollers, said belt comprising a relatively narrow and heavy under or base strip 4 and a relatively wide and flexible strip 5 secured thereon; the outer surface of the strip 5 being formed to give a non-slip surface preferably by means of pyramid shaped teeth 6 such as are featured in said above mentioned patent. The upper run of the belt strip 5 for the greater portion of its length

is made to turn up at the sides and so as to be of concentric form and substantially semi-circular in cross section, as shown in Fig. 3, by longitudinally extending guide plates 7 having a similar curvature. These plates are disposed to the sides of the main base strip 4 and are supported from the frames 2 by suitable brackets 8. Said main strip 4 may if desired rest intermediate the rollers on a flat member 9 supported from said frames 2, so that the main weight and pressure on the belt will be taken by said member and the strip 4 rather than by the guides and the flexible strip 5. One of the rollers 3 is driven by any suitable means so as to drive the belt.

Disposed above the guides and the corresponding concaved portion of the belt are transversely spaced horizontal bars 10 which are suspended from the uprights 1, for transverse rocking movement, by pivoted arms 11 depending from and connected to said uprights 1. These bars support rollers 12 adjacent their ends, about which an endless transversely flat belt 13 is disposed. This belt is somewhat wider than the belt below when the latter is concaved and its outer surface is also formed with pyramidal teeth 14 or other means to provide a non-slip grip on the material. The lower run of the belt 13 is spaced a certain distance from the under belt or so that it is well clear of the upper edges of the concaved portion of said lower belt. The upper belt is rocked transversely through a certain stroke and at the same time is driven lengthwise by the following means.

Journalized in a bracket 15 secured to one of the uprights 1 outwardly of the same is a horizontal shaft 16 which extends lengthwise of the machine and is adapted to be driven by any suitable means. On one end this shaft carries a crank or eccentric 17 which engages the adjacent end of a horizontal connecting rod 18 which extends transversely of the machine and is connected to the adjacent belt supporting bar 10 at a convenient point. A bevel gear 19 fixed on the opposite end of the shaft meshes with another bevel gear 20 journaled in the bracket 15 and arranged on a horizontal transverse axis. The axis of the gear 20 is substantially alined

with the axis of one of the rollers 12 and is operatively connected thereto by a special shaft. The portion of this shaft nearest said roller and connected thereto is in the form 5 of a closely wound helical spring 21, while the outer portion 22 is rigid and has a sliding but a non-turning fit in the hub of the gear 20. With the rotation of the shaft 16 the upper belt unit is reciprocated transversely relative to the lower belt. The shaft 22 being 10 slideable in the gear 20 permits the belt roller to be rotated with such reciprocating movement of the same without disturbing the position of the gear; while the universally 15 silent driving spring portion 21 of the shaft takes care of the slight variation in the vertical plane of the axis of the roller had with the reciprocating movement of the same, without any binding and without the use of 20 a pair of universal joints. The two belts are driven in such a direction that their adjacent runs both travel in the same direction.

The lumps 23 to be rolled are dropped in spaced relation onto the flat portion of the 25 lower belt at one end from the spout 24 of a pressing and measuring machine, such as that for instance shown in my co-pending application for patent, Serial No. 455,237, filed May 24, 1930. It is of course necessary 30 that the lumps or the belts shall be dusted in order to prevent the adhesion of the material thereto. This feature however has previously been recognized as being necessary and provision being made for taking care of 35 the same, and hence forms no part of this invention. As the lumps advance along the belt and the latter assumes a concave form, said lumps are engaged by the longitudinally and transversely moving upper belt, which 40 causes the lumps to be lowered up and down the concave surface, while being moved lengthwise of the same, until by the time said lumps pass beyond the upper belt they are in a substantially spherical form, as shown at 45 25. The relatively great curvature of the lower belt as differentiated from the flat curve of the corresponding belt of the previous device, prevents any possibility of the lumps being squeezed or wedged between the 50 belts toward their outer edges; while the special form and mounting of said belt enables such great curvature to be obtained without any stretch or distortion of the belt being had when passing about the end rollers.

55 It is here to be noted that the upper belt is driven at a somewhat greater speed than the lower belt in contradistinction to the arrangement employed in the previous Patent No. 1,303,013, hereinbefore referred to. 60 This difference in drive speeds of the belts increases the capacity of the machine to a material degree, as well as avoiding the possibility of the lumps contacting with each other as they are worked between the belts. 65 This is because the faster travel of the upper

flat belt tends to speed up the longitudinal movement of the lumps being rolled back and forth on the lower belt. This separates the lumps relative to their initial spacing rather than retarding them as was found to be the case with the reverse arrangement of the previous patent. This permits the lumps to be initially fed onto the belt in closer relation to each other than would otherwise be the case, without danger of the lumps subsequently coming together, and the output of the machine is of course correspondingly increased.

70 From the foregoing description it will be readily seen that I have produced such a device as substantially fulfills the objects of the invention as set forth herein.

75 While this specification sets forth in detail the present and preferred construction of the device, still in practice such deviations from such detail may be resorted to as do not form a departure from the spirit of the invention, as defined by the appended claims.

80 Having thus described my invention what I claim as new and useful and desire to secure by Letters Patent is:

85 1. A plastic rolling machine including upper and lower endless belts between the adjacent runs of which the material to be rolled passes, the upper run of the lower belt along that portion of the same under the upper belt having a substantially semicircular concave form in cross section relative to the upper belt and being narrower between its side edges than the upper belt, and means to reciprocate said upper belt transversely.

90 2. A plastic rolling machine comprising upper and lower endless belts between the adjacent runs of which the material to be rolled passes; rigid frame uprights to the sides of the belts intermediate their ends and projecting above the upper belt, and rollers about which said upper belt passes, side supporting bars for said rollers, arms pivoted on and depending from the uprights to and supporting said bars for transverse swinging movement, a horizontal driven shaft mounted in connection with one of the uprights and extending longitudinally of the belts, a crank connection between said shaft and the adjacent bar, a flexible shaft unit connected to and extending axially from one of the rollers, a gear mounted in fixed relation with the first named shaft axially of the second shaft and with which the outer end of the latter has slideable driving connection, and a gear on said first named shaft driving said first named gear.

95 In testimony whereof I affix my signature. 125
GEORGE K. BAINBRIDGE.
